(57) **CLAIM**

The ornamental design for a magnetic carrier for a rehanger, as shown and described.

DESCRIPTION

FIG. 1 is a back view of the magnetic carrier for a rehanger showing the new design.

FIG. 2 is a bottom view of the new design.

FIG. 3 is a front view of the new design.

FIG. 4 is an isometric view of the new design.

FIG. 5 is a left side view of the new design.

FIG. 6 is a right side view of the new design; and,

FIG. 7 is a top view of the new design.
